PISTON EXPANDING APPARATUS

David Rubin, Scranton, Pa., assignor to Scranton Industrial Development Company, Scranton, Pa., a corporation of Delaware

Original application December 1, 1937, Serial No. 177,569. Divided and this application August 29, 1939, Serial No. 292,499

1 Claim. (Cl. 153—80)

This invention relates generally to devices for decreasing the clearance of pistons in the cylinders of internal combustion motors and more particularly to machines for expanding the pistons of such motors.

This application is a division of my application Serial Number 177,569, filed December 1, 1937, now Patent 2,174,217, dated September 26, 1939, and a continuation-in-part of my application Serial Number 118,964, filed January 4, 1937.

Internal combustion engines after a certain amount of use, lose compression and power owing to the fact that the piston rings, cylinder wall and piston skirt become worn down. The cylinder may be rebored and new rings and piston installed, but it is cheaper to replace the worn rings with new ones and use the old piston. The old piston, because of its relatively reduced diameter, oscillates about the piston pin and between the cylinder walls giving rise to what is known as "piston slap." It is well known to insert a resilient expansive device within the piston skirt to enlarge the same, but this is unsatisfactory for many reasons, including the facts that insufficient enlargement is obtained and the characteristics of the piston are altered.

Inasmuch as the new piston rings provide increased compression, I have found that if the piston skirt is expanded transversely of the piston pin, "piston slap" is removed and oil consumption is considerably reduced. I have also found that if instead of being expanded, the piston skirt is ovalized (a reduction of the skirt diameter, longitudinally of the piston pin and a corresponding increase in piston skirt diameter transversely of the pin) an improved motor performance is obtained. Where the piston skirt is slotted a combination of expanding and ovalizing is very satisfactory.

While it has been proposed to expand piston skirts by hammering or "peening" them to an expanded shape, this has been unsatisfactory in that insufficient expansion is produced and the peening causes the metal to crystallize and become brittle.

The present invention contemplates the physical expansion of the piston skirt while the same is in a heated and annealed condition. After the stretching operation is completed, the piston is retempered so that its original metallic condition is restored but the new shape is retained. The metal heating and treatment varies with the metallic composition of the piston.

In my prior Patent No. 2,133,403 I have disclosed and claimed a method of expanding pis-

tons, such method involving certain steps of heating, stretching, and cooling. The invention disclosed and claimed in the present application relates more especially to apparatus for expanding pistons, e. g., in accordance with the method disclosed in my aforementioned patent. It will be understood, however, that apparatus embodying my present invention is not restricted in use to the practice of the particular method referred to.

The main object of the present invention is the provision of structure whereby a simple, efficient and inexpensive device accurately expands pistons of various types under close control.

Another object is to provide apparatus of the character referred to including a measuring device so correlative arranged with respect to the piston forcing or expanding parts as to be conveniently movable to operating position and to be capable of indicating accurately the amount of expansion effected.

Other objects will become apparent from a reading of the following description, the appended claim, and the accompanying drawings, in which:

Figure 1 is a fragmentary plan view of one preferred embodiment of the invention;

Figure 2 is a fragmentary elevational view of Figure 1;

Figure 3 is an enlarged fragmentary elevational view of the front of the machine shown in Figure 1;

Figure 4 is an elevational front view of an alternate type of piston expanding peg;

Figure 5 is a sectional view of Figure 4 as seen from the plane 5—5 thereon;

Figure 6 is a bottom view of the moving piston peg shown on Figure 3 as seen from the plane 3—3 thereon;

Figure 7 is a top plan view of a further preferred embodiment of the invention;

Figure 8 is a view in side elevation of the embodiment shown in Figure 7;

Figure 9 is a longitudinal vertical sectional view taken on the line 9—9 of Figure 7;

Figure 10 is a vertical cross sectional view taken on the line 10—10 of Figure 7; and

Figure 11 is a detail perspective view of a piston-engaging abutment.

Form shown in Figures 1 to 6 inclusive

Referring first to the embodiment shown in Figures 1 to 6 inclusive, there is shown a casing or frame 10 supporting the operating parts and having a top 11 which serves conveniently as a stationary work table. The front and back walls

12 and 13 respectively and the side walls 14 and 15 may be sufficiently extended downwardly to enclose the heating and tempering ovens (not shown) for treating the pistons before and after stretching.

The stretching or expanding assembly, generally indicated by numeral 16, is composed essentially of a stationary arm 17 and a moving arm or carrier 18 upon which are detachably mounted a stationary piston expansion abutment or peg 19 and a movable piston expansion abutment or peg 20, respectively. Stationary arm 17 is of rigid construction and is securely mounted, by means of two bolts 21, to the bottom surface of top 11 and projects horizontally forward through the left end of a horizontally disposed oblong orifice 22 in front wall 12. Moving arm 18 is the load arm of a long lever or carrier 24 mounted similarly to arm 17, but is pivotally connected to top 11 by means of bolt 23 which threadedly engages the underside of said top similarly to bolts 21. The rear end of lever 24 has a nut 25 pivotally attached thereto, and the nut in turn is threadedly mounted on a transversely mounted screw 26. Screw 26 is trunnioned in side walls 14 and 15 and penetrates the latter to have a large hand wheel 27 affixed to the terminal thereof. Sufficient clearance 28 is provided, longitudinally with respect to lever 24, to allow for the arcuate travel of the rear end of said lever, so that the manual actuation of hand wheel 27 will result in the arm 18 and peg 20 slowly and powerfully approaching or receding from arm 17 and peg 19, depending upon the direction of rotation of the hand wheel.

It is, of course, apparent that other means of actuation of arm 18 may be employed, such as hydraulic, or compound lever means, but the means described above have been found efficient and inexpensive.

The abutments or pegs 19 and 20 may be identical in construction and interchangeable; hence a description of peg 19 will suffice for both. The working face 55 is plane, vertical, and transversely disposed with relation to the principal direction of motion of peg 20. Face 55 is provided with a horizontal rabbet 56 at the lower edge thereof, and a horizontal groove 57. The purpose of these depressions is to permit horizontally disposed reinforcing ribs on the internal surfaces of the piston skirt to fit therein so that the expanding pressure may be exerted against the relatively smooth portions of the cylindrical inner walls of the piston skirt. The placement of these depressions may be varied to suit the individual requirements of different types of pistons but the configuration shown in Figure 3 has been found satisfactory for nearly all ordinary pistons. The inner face 58 is provided with a deep rabbet 59, preferably curved at 59' so that the strain is evenly distributed and the likelihood of breakage is reduced. An integral shank 60 threaded adjacent the end thereof, penetrates a vertically disposed orifice in arm 17 and a nut 61 when tightened down securely clamps the peg 19 in place. Peg 20 is similarly attached to the arm 18.

In Figures 4 and 5 there is illustrated an alternate type of peg. This peg 62 has a working head 63 which is adapted to swivel about the pivot 64 and the working face 65 has a cylindrically shaped surface. The peg 62 is substituted in place of peg 20 when the piston skirt is of a type having vertically disposed reinforcing ribs, or when the piston skirt is provided with a diagonally dis-

posed slot. The face 65 is adapted to fit between the said vertical ribs or to distribute pressure over a sufficiently large area around the diagonal slot so that the skirt is not fractured. The curvature of face 65 may be altered to coincide with the configuration of different pistons, where advisable. Peg 62 is provided with a shank 60' which is inserted in the opening in the forward end of arm 18 and is secured with the nut 61'. Pivot head 64' prevents the head 63 from slipping off while shoulder 64'' provides a smooth bearing surface in place of the upper face of arm 18, so that the head 63 may readily rotate.

A clamping device 29 is used to hold the piston to the stationary peg 19 before and after the piston is acted on by peg 20 so that the piston will not become displaced and in order that accurate measurements may be made before, during, and after the stretching or expanding operation. This device 29 comprises a support arm 30, and a clamping face plate 31. Since the piston is comparatively light and the pegs 19 and 20 maintain it in place while the piston is being expanded, the clamping device need not exert very great pressure. The face plate 31 is supported by an integral rod 32 perpendicularly projecting from the rear thereof to penetrate the forward end of support arm 30, and terminate in the operating knob 33. A spiral expansive spring 34 serves to force the face plate 31 against the piston skirt and clamp it against peg 19. The support arm 30 is adjustably clamped at the rear end thereof to arm 17 by means of the thumb-screw 35. The forward portion of arm 30 is offset so that a sufficient clearance is provided for the insertion of the piston skirt and the operation of the face plate 31.

A measuring device 36 is provided for readily and accurately determining the amount of expansion given the piston skirt. Such a device comprises preferably a rim-set dial micrometer 37 whose feeler 38 is adapted to contact the outer surface of the piston skirt on a line with the centers of pegs 19 and 20. The body of the micrometer 37 is adjustably mounted by virtue of the following assembly. Bolt 39 which freely penetrates top 11, and pivotally carries the rear end of arm 41 may be tightened in position by thumb-nut 40. Arm 41 penetrates orifice 22. A spacer 42 has two integral screw ends of reduced diameter, the upper one of which penetrates an orifice in the forward end of arm 41 and is adjustably clamped by a thumb-nut 43; and the lower one of which penetrates an orifice in the rear end of arm 44 and is adjustably clamped by a thumb-nut 45. The forward end of arm 44 is adjustably and pivotally connected to the micrometer by the integral threaded shank 46 depending from said micrometer which penetrates said arm and is clamped by thumb-nut 47. Wherever desirable, the spacer 42 may be made adjustable, or other suitable mechanism may be utilized for varying the effective height of the micrometer.

An adjustable work table 48 is vertically regulable for supporting pistons of different heights and is pivotally mounted in a horizontal plane so that it may be swung into and out of position as needed. The horizontal face 49 is supported by an integral vertical post 50 which is in turn clamped in the bifurcated end of an arm 51, the rear end of which is pivotally mounted on an inverted L shaped bracket 52 affixed to the front wall 12. Actuation of thumb-screw 53 allows adjustment in a horizontal plane and actuation of

thumb-nut 51 allows adjustment in a vertical plane.

Operation [of the form shown in Figures 4 to 6]

Knob 33 is pulled out and the heated piston is placed up under pegs 19 and 20 with the piston pin parallel to the arm 11, and the skirt outside of the pegs, whereupon knob 33 is released. The table 48 is swung underneath the piston head and adjusted to support the piston in the position indicated by the dash-single-dot lines on Figure 3. The measuring device is adjusted so that the feeler 38 contacts the outer wall of the piston skirt and is properly aligned as set forth above. The micrometer is adjusted to zero reading. Hand-wheel 29 is manipulated and the desired expansion or stretch is given to the piston skirt as the peg 20 moves away from the peg 19. This procedure is then reversed and the piston is removed.

It may now be noted that the connecting rod and piston assembly may be treated without removing the connecting rod from the piston. The connecting rod is placed between the arms 11 and 18 while the piston pin and connecting rod knuckle find no obstruction because of the rabbits 39.

The machine is shown set up of Figures 1, 2, and 3 for operating on pistons with the piston head down. In this arrangement it is easy for the operator to see into the piston and carefully adjust same with relation to the pegs. Where it is desired, however, the pegs 19 and 20 may be inverted and the clamping device swung up to take the position indicated by the dash-double-dot lines on Figure 3. The measuring device may also be raised by reversing the positions of arm 48 and spacer 42. In this position the piston is treated with the head up, and is placed as indicated by the dash-triple-dot lines on Figure 3.

Form shown in Figures 7 to 11 inclusive

Figures 7 to 11 inclusive show a further preferred embodiment of the invention which is somewhat similar in general structural arrangement and mode of operation to the form shown in Figures 1 to 6 inclusive, but which also includes other advantageous features.

In the embodiment shown in Figures 7 to 11, which may be carried upon a support S, there is provided a frame generally designated 100 which conveniently may be fabricated of side track or guide members 101-102 spaced apart at their left hand ends, as viewed in Figures 7, 8, and 9, by means of a block 103 to which the side members are secured by bolts 104. At their right hand ends the guide members 101-102 are connected together in spaced relation by means of a cross piece 105 and bolts 106.

A carrier or cross head generally designated 107 is mounted for sliding movements on the guide members 101-102. In the form shown, the cross head comprises a block 108 and upper and lower plates 109 secured to the block by means of bolts 110. The plates 109 extend laterally beyond the sides of the block to provide flanges 111 adapted to ride on the upper and lower surfaces of the guide members 101-102. Preferably, the block 108 is of a thickness, measured vertically, somewhat less than the height of the guide members, the plates 109 being spaced slightly from the top and bottom faces of the block by means of replaceable shims 112. This

arrangement provides for adjusting the position of the block 108 with respect to the guide members so as to properly position or align the block relative to the guide members, one alternative being.

Any suitable power or manually operated means may be provided for moving the carrier or cross head along the guide members. In the form shown, there is provided a screw 113 having an eye 114 positioned in a recess 115 in the cross head block 108, and a bolt 116 secured to the cross head and passing through the eye. The outer end of the screw extends through the internally threaded sleeve 117 journaled in the cross piece 105 of the frame and being provided with a crank 118.

Piston-engaging abutments in the present instance comprising pegs 119-120 are carried by the blocks 103 and 108, being respectively secured thereto by studs as in the first form of the invention. The arrangement is such that a piston P shown fragmentarily in Figure 9 is positioned over the pegs 119 and 120 with the lower surface of the piston skirt resting upon the frame and block 108. The pegs 119 and 120 are arranged to contact respectively with opposite surface portions of the inside of the piston skirt, so that, upon relative separating movement of the pegs, effected by rotation of the screw and movement to the right of the cross head, the pegs will press outwardly against the skirt at diametrically opposite sides thereof so as to stretch or expand the skirt. Preferably, the pegs extend well into the piston and have contact with the inner surface of the skirt over a substantial area considered longitudinally of the piston axis. Many present-day pistons are provided with internal stiffening projections, such as beads or ribs, and the piston P is disclosed as having such a rib designated p.

In order to provide for the extended contact area between the pegs and skirt of a piston provided with such a projection, the pegs are formed with recesses or depressions 119^a and 120^a respectively adapted to accommodate the projection p, at the same time permitting the remainder of the operative face of each peg to lie snugly against the inner surface of the piston skirt.

The pegs themselves are so constructed as to provide for adjustment of the piston-engaging surfaces thereof in a manner to permit a very accurate alignment of the pegs with respect to the piston surface, and with respect to each other. A preferred construction making such adjustment possible comprises pegs 119 and 120 formed with splits at 119^b and 120^b respectively, thus providing fork-like or bifurcated members. Thus the peg 119, by virtue of the split, is formed with a relatively heavy part 119^b and a relatively light part 119^c. A screw 119^d having threaded engagement with the heavy part 119^b engages the lighter part 119^c, so that operation of the screw springs the lighter part relative to the heavier part, thus effecting a change in the alignment of the lighter or piston-engaging part with respect to the piston skirt and with respect to the piston-engaging part of the peg 120. Similarly, the peg 120 is formed with a relatively heavy part 119^b and a relatively light part 119^c, being provided also with an adjusting screw 119^d.

It will be observed that, by changing the thickness of the shims 112 which are interposed between the cross head block 108 and cross head plates 109, a primary adjustment of the cross head, and consequently of the peg 120, may be effected. After such primary or relatively coarse adjustment has been made, a final and finer adjustment

of the alignment of the piston-engaging surfaces of the pegs may be made by operation of either one or both of the screws 119^a and 120^a. These adjustments are particularly convenient and important when the apparatus is used for expanding pistons of various designs. I have found that the inner surfaces of the skirts of different types and makes of pistons taper axially of the pistons to varying degrees. The adjustments provided as described above make it possible to expand various kinds of pistons without providing special abutments for each particular design of piston.

In accordance with the invention, the embodiment disclosed in Figures 7 to 11 inclusive also is provided with an indicator gauge or the like for measuring or indicating the amount of stretching or expansion of the piston being worked upon. As shown, a dial gauge 121 having a feeler 121^a is mounted upon a screw 122 having threaded engagement with a bracket 123 secured to the frame by means of a screw 124. A lock nut 125 on the screw 124 serves to clamp the bracket 123 in adjusted position, and a lock nut 126 on the screw 122 serves to clamp the screw and hence the gauge in adjusted position with respect to the bracket. The gauge body thus is so mounted as to be adjustable relative to the frame. In use, the gauge is adjusted or moved to such position that the feeler 121^a engages the outer surface of a piston skirt prior to expanding thereof. Then the screw 113 is rotated to move the cross head to the right so as to effect relative separating movement of the abutments and stretching of the piston until the gauge indicates that the predetermined desired amount of stretching has taken place.

Operation (of the form shown in Figures 7 to 11 inclusive)

To recapitulate the mode of use and operation 40 of the embodiment shown in Figures 7 to 11, it will be assumed that the parts are in the position shown in Figures 7 and 8. The first step

is to operate the screw 113 so as to move the cross head and abutment peg 120 toward the left until the distance between the outer faces of the pegs 118 and 120 is considerably less than the inside diameter of the piston skirt. The piston is then placed over the pegs, and, if it is found that the outer faces of the peg portions 118^a and 120^a do not align with the associated inner piston skirt portions, the necessary adjustments of one or both of the pegs are effected in the manner already described. The gauge is then set so that the feeler 121^a engages the outer surface of the piston, and the screw is rotated in the opposite direction until the gauge shows that the proper amount of stretching has taken place. Thereafter the screw is again rotated to move the cross head to the left so that the piston may be removed from the apparatus.

The apparatus shown herein embody the invention in preferred and commercially successful forms, but it is to be understood that changes may be made without departing from the invention as defined in the claim.

I claim:

A piston skirt expanding machine including a stationary casing; an arm fixedly attached to said casing; a movable arm attached to said casing and adapted for movement toward and away from said stationary arm, said movement being rectilinear in at least one plane; a pair of pegs for engaging the inside surface of a piston skirt, said pegs being mounted one on each arm; and a measuring device having a feeler movable in substantially the same direction as the movable arm, said device being adjustably mounted on said casing whereby the same may be rigidly positioned, so that the feeler may contact the outside of said piston skirt adjacent the peg of the movable arm, and register the amount of movement in said skirt portion in said plane, caused by the peg on the movable arm.

DAVID RUBIN.
